UNITED STATES PATENT OFFICE

136,761

DESIGN FOR A TYPEWRITING MACHINE

John Joseph Kittel, St. Albans, N. Y., assignor to
Royal Typewriter Company, Inc., New York,
N. Y., a corporation of New York

Application September 4, 1943, Serial No. 111,064

Term of patent 14 years

To all whom it may concern:

Be it known that I, John Joseph Kittel, a citizen of the United States, residing at St. Albans, in the county of Queens and State of New York; have invented a new, original, and ornamental Design for Typewriting Machine, of which the following is a specification, reference being had to the accompanying drawings, forming part thereof.

Figure 1 is a front perspective view of a typewriting machine, showing my new design.

Figure 2 is a rear perspective view of the mask only thereof.

Figure 3 is a side elevational view thereof.

The essential features of my design are shown in solid lines on the drawings.

I claim:

The ornamental design for a typewriting machine, as shown and described.

JOHN JOSEPH KITTEL.
